United States Patent Office

Des. 190,690
Patented June 20, 1961

190,690

MOTION PICTURE CAMERA

Robert L. Smith, Deerfield, Ill., assignor to Bell & Howell Company, Chicago, Ill., a corporation of Illinois

Filed Mar. 20, 1961, Ser. No. 64,393

Term of patent 14 years

(Cl. D61—1)

FIG. 1.

FIG. 2.

I claim:

The ornamental design for a motion picture camera, as shown.
